UNITED STATES PATENT OFFICE.

JACOB ELSON, OF NEW YORK, N. Y.

COLLAR-HOLDER.

1,347,999.

Specification of Letters Patent. Patented July 27, 1920.

Application filed March 26, 1920. Serial No. 369,033.

To all whom it may concern:

Be it known that I, JACOB ELSON, a citizen of the United States, residing at New York city, borough of Bronx, county of Bronx, and State of New York, have invented a certain new and useful Collar-Holder, of which the following is a specification.

This invention is a collar holder intended, 10 more particularly, to maintain the ends of the fold over portions of a soft fold over collar in proper distended relation to one another.

Devices of this general character have 15 been heretofore suggested and quite a number of them have gone into use. However, all of these prior devices have been open to one or more disadvantages which have more or less reverted against their use by 20 discriminating persons. Quite a number of collar holders which have been found on the market are provided with oppositely extending resilient jaws, each of which is adapted to grip one end of the fold over 25 portion of the collar, but practically all of said devices either grip the collar too tightly or not tightly enough. The inability to obtain the desired frictional grip of the collar is due to the fact that, because of 30 the relatively short distance between the ends of the fold over portion thereof, sufficient resiliency cannot be secured in a relatively straight metallic member and when the holders are made light enough to give 35 the desired resiliency, they are not strong enough to tightly grip the collar in frictional engagement, and have a tendency to become disengaged and lost.

For this reason, other holders have been 40 suggested which positively grip the collar between sharpened prongs or other relatively sharp surfaces, but these expedients tear the collar and have therefore not gone into extensive use.

45 The object of the present invention is to provide a collar holder, which will possess the necessary strength, and will, nevertheless, embody the required resiliency and force to grip the collar tightly through 50 frictional engagement therewith.

Features of the invention, other than those specified, will be apparent from the hereinafter detailed description and claims, when read in conjunction with the accompanying drawings.

The accompanying drawings illustrate one

practical embodiment of the invention, but the construction therein shown is to be understood as illustrative, only, and not as defining the limits of the invention. 60

Figure 1 shows a soft fold over collar, with which is associated a holder embodying the present invention.

Fig. 2 is a perspective view showing the holder detached; and, 65

Fig. 3 is an edge view of the holder.

The holder of the present invention embodies two members 1 and 2, which may be referred to as the front and back member respectively and these two members 70 may be conveniently formed from resilient strip metal, preferably from one of the precious metals, such as gold or silver, or gold or silver plated steel or brass. The front and back members 1 and 2 are soldered together intermediate their ends, so that the opposite ends of the holder thus formed constitute two pair of clips, one of which is adapted to engage with one of the ends of the fold over portion of the collar as 75 shown in Fig. 1. A portion of the forward face of the back member 2 is preferably milled or knurled as shown at 3, so as to better grip the collar on the back side of the fold over portion thereof, but the 80 back face of the front member 1 is preferably left smooth so as not to mar the face of the collar.

The front jaws of each of the clips referred to may be made straight or curved 90 along flowing lines, but the back plate 2 is preferably bent to form off sets 4 adapted to straddle over the hem of the collar and position the knurled portion 3 of each clip jaw interiorly of the hem. This assures of 95 proper co-operation between the clamping jaws and permits the collar to be gripped tightly in such an efficient frictional manner as to positively preclude the disengagement of the holder from the collar. 100

Holders provided with oppositely extending clips have been heretofore suggested, but difficulty has been exposed in obtaining the proper resiliency when sufficiently heavy material is used. I overcome this disadvantage in the present invention in a simple and economical manner by forming the central portion of the holder into a loop 5. At the back portion of this loop I solder, rivet or otherwise secure the front and back plates 110 1 and 2 together leaving the remaining portions of the members free from attachment

to one another. By forming the loop 5 as shown intermediate the ends of the holder, maximum resiliency is imparted to the holder and particularly to the clamping 5 jaws of the opposite ends thereof. The stock from which the holder is made may be much heavier than has heretofore been possible, yet the resiliency resulting from the use of the loop as shown will permit of the 10 ready manual attachment or detachment from the collar but will cause the holder to grip the collar so tightly during use that it cannot possibly become inadvertently disengaged therefrom. The spring loop 5 does, 15 in nowise, interfere with the collar button or the association of a neck tie with the collar, and may be made of various sizes but, naturally, the larger said loop is made the greater will be the resiliency and the heavier the stock from which the holder may be 20 constructed.

It will be understood that the specific invention described may be modified in formal respects, such as by the substitution of 25 equivalents, and that parts of the complete mechanism described may be used alone, or in other environments, without departing from the spirit or substance of the broad invention, the scope of which is commensurate with the appended claims.

Having thus fully described the invention, what I claim as new and desire to secure by Letters Patent is:

1. A holder for soft fold over collars embodying a front plate and a back plate secured together intermediate their ends and provided intermediate their ends with a looped portion from the opposite sides of which extend two resilient clips, the looped 40 portion serving to impart resiliency to the clips associated therewith, whereby they are the better enabled to grip the fold over portion of the collar.

2. A holder for soft fold over collars em-

bodying a loop at its center and a pair of 45 resilient arms extending laterally from either side of the loop and forming a pair of clips adapted to grip the ends of the fold over portion of the soft collar, the looped portion of the holder serving to impart resiliency to the clip portions of said holder. 50

3. A holder for soft fold over collars embodying a pair of clips adapted to grip the opposite ends of the fold over portion of 55 said collar, and a looped spring member uniting the clips and imparting resiliency thereto.

4. A holder for soft fold over collars embodying a front member and a back member provided at their centers with interfitting spring loops, and means for securing 60 said members together at the looped portions thereof, whereby the opposite ends of the holder constitute two spring clips, a portion of the forward face of the back member 65 on either side of the spring looped portion thereof being knurled to tightly grip the fold over portion of the collar on the concealed face thereof.

5. A holder for soft fold over collars embodying a front member and a back member provided at their centers with interfitting spring loops, and means for securing 70 said members together at the looped portions thereof, whereby the opposite ends of the holder constitute two spring clips, a portion of the forward face of the back member 75 on either side of the spring looped portion thereof being knurled to tightly grip the fold over portion of the collar on the concealed face thereof, and the back face of the front member being smooth so as not to deface or mar the exposed surface of the collar.

In testimony whereof, I have signed my 85 name to this specification.

JACOB ELSON
